MEANS FOR MINIMIZING INDUCTIVE INTERFERENCE.

1,196,302.

Specification of Letters Patent. Patented Aug. 29, 1916.

Application filed January 2, 1915. Serial No. 172.

To all whom it may concern:

Be it known that I, CHARLES F. SCOTT, a citizen of the United States, and a resident of New Haven, in the county of New Haven 5 and State of Connecticut, have invented a new and useful Improvement in Means for Minimizing Inductive Interference, of which the following is a specification.

My invention relates to improvements in 10 means whereby electric current flow may be substantially confined to certain conducting paths in preference to other paths which may be of lower impedance and which may be electrically connected in parallel relationship therewith.

More particularly, my invention relates 15 to improvements in means whereby the return flow of trolley currents of a railway system may be substantially confined to the 20 track rails in preference to ground or earth return. As fully explained in my patent application, Serial No. 170, filed concurrently herewith and assigned to the Westinghouse Electric & Manufacturing Company, by thus confining the return flow of 25 trolley currents to the track rails, inductive disturbances which arise from currents flowing in the railway system, and which may be imposed upon an intelligence-trans- 30 mission circuit disposed in proximity thereto, may be greatly minimized. Moreover, electrolytic corrosion of gas mains, water mains, etc., which might result from the flow through earth of currents that origi- 35 nate in railway systems, is substantially avoided.

To this end, I have proposed that series 40 transformers be inserted at spaced intervals in a railway system, the primary wind- 45 ings of the transformers being connected across insulating joints and in series-circuit relationship with the trolley conductor, and the secondary windings, having preferably the same number of turns as the aforementioned primary windings, being connected at corresponding points in the rail circuit and across insulating joints that divide the rail circuit into a plurality of track sections which are insulated from 50 one another. By this means, electromotive forces are impressed, at intervals, upon

the track rails, thereby compensating for their impedance which is occasioned by their inherent properties. As a result, the currents flowing in the trolley circuit and 55 in the rails may be made equal because of the relationship existing between the ampere turns of the primary windings and of the secondary windings of the transformers.

Inasmuch as the impedance of the track 60 comprising a single rail or a pair of rails is substantially high, under all conditions, it is advisable, when other track rails are available, to interconnect electrically all of the tracks in such a manner that they may 65 be used concurrently as paths for the return flow of the trolley currents.

By means of my present invention, I sub- 70 stantially decrease the impedance of a track, which is paralleled and adjacently disposed to other tracks, by interconnecting certain portions thereof in parallel relationship, and, at the same time, I insure confinement 75 of the trolley currents to these tracks by inductively interlinking them with the trolley conductor.

For a better understanding of the nature 80 and scope of my invention, reference may be had to the following description and the accompanying drawing in which the single 85 figure is a diagrammatic representation of a railway system embodying a form of my invention.

Referring to the drawing, a source of 90 power supply 1, shown as a single-phase alternator, is connected to trolley conductors 2 and 3, and to the track rails 4 and 5, which are associated respectively with the aforementioned trolley conductors. In each 95 trolley conductor 2 and 3, I insert, at spaced intervals, series transformers 6, primary windings 7 thereof being connected in series-circuit relationship with the trolley conductors, and secondary windings 8 being connected across insulating joints 9 dis- 100 posed at corresponding points in the track rails 4 and 5. As shown in the drawing, each track 4 and 5 comprises two rails 10 which are more or less in contact with the earth, as is usual with all railway systems.

As explained above, a track comprising a single rail or a pair of rails has consider-

able impedance, and, inasmuch as the two tracks 4 and 5 are disposed adjacent to each other, it is desirable to interconnect them in such a manner as to lower the impedance 5 of the path for the return flow of the trolley currents. At the same time, it is desirable to minimize the inductive disturbances upon intelligence-transmission circuits 11, shown as telegraph circuits, which are so 10 disposed as to be under the inductive influences arising from the currents flowing in the railway systems.

To this end, the tracks 4 and 5 are electrically interconnected by means of bonds 12 15 extending between alternate sections of the tracks, as shown in the drawing. To illustrate, assume that the transformers 6 are spaced one mile apart in each railway system. For the mile intervening between the 20 source of power supply 1 and the first series transformers inserted in the railway systems, the tracks 4 and 5 are electrically independent of each other. For the mile intervening between the first and second series 25 transformers, the tracks 4 and 5 are electrically interconnected in parallel relationship by means of the bonds 12. Similarly, alternate sections of the railway systems along the entire right-of-way are interconnected. 30 As a result, current flowing from a moving vehicle upon one of the railway systems will traverse a single track in alternate rail sections, and all of the tracks connected in parallel relationship, in the other rail sections. 35 Consequently, the impedance of the return conductor for the trolley currents is considerably reduced, and the tracks 4 and 5 are so interconnected that unduly high differences of potential cannot exist between them. 40 In commercial installations, it may be necessary to compensate for the irregular spacing of the intelligence-transmission conductors 11 relative to the railway systems. For this reason, I have shown the primary 45 and secondary windings of the transformers 6 as provided with a plurality of taps 13 by means of which the ratios of the turns of the primary and secondary windings may be regulated so as to force certain currents 50 to flow through the earth. These earth currents may be so adjusted as to induce electromotive forces in either direction in the telegraph conductors 11, and hence, are utilized for correcting or neutralizing certain 55 other electromotive forces which may be induced therein by reason of the unequal spacing of the telegraph circuit from the trolley circuits and the track circuits.

While I have shown my invention as applied to two railway systems, it will be understood that it may be utilized with any number of railway systems or tracks which may be paralleled along the same right-of-way.

I claim as my invention:

65

1. A railway system comprising a source of current supply, a trolley conductor connected thereto, a conductor comprising a plurality of parallel tracks, spaced insulating joints correspondingly inserted in each 70 track to form a series of rail sections insulated from one another, transformers to interlink inductively the trolley conductor with some of said tracks, and conducting bonds to electrically connect alternate rail 75 sections of all said tracks.

2. A railway system comprising a source of current supply, a trolley conductor connected thereto, a conductor comprising a plurality of tracks, spaced insulating joints 80 correspondingly inserted in each track to form a series of rail sections insulated from one another, transformers to inductively interlink said trolley conductor and some of said tracks, and conductors for electrically 85 connecting in parallel relationship alternate rail sections of all said tracks.

3. A railway system comprising a source of current supply, a trolley conductor connected thereto, a conductor comprising a 90 plurality of tracks, spaced insulating joints inserted in each track to provide a series of rail sections insulated from one another, electrical connections to connect alternate rail sections of all the tracks in parallel 95 relationship, and means to inductively interlink some of the tracks with the said trolley conductor.

4. A railway system comprising a source of current supply, a trolley conductor connected thereto, a conductor comprising a plurality of tracks, spaced insulating joints 100 inserted in each track to provide a series of rail sections insulated from one another, electrical connections extending between alternate rail sections of all the tracks, and transformers having primary windings inserted at intervals and in series-circuit relationship with said trolley conductor and secondary windings connected in shunt to the 105 insulating joints in some of the tracks.

5. A system of distribution comprising a source of current supply, a conductor connected to one terminal thereof, a plurality of conductors connected to the other terminal, said second conductors constituting a 110 series of conducting sections insulated from one another, means serving to impress electromotive forces, at intervals, upon some of said second conductors, and means for connecting, in parallel relationship, certain sections of all of said second conductors.

6. A system of distribution comprising a source of current supply, a conductor connected to one terminal thereof, a plurality of 115 conductors connected to the other terminal, each of said second conductors comprising a series of conducting sections insulated from

one another, means serving to inductively interlink said first conductor with some of said second conductors, and means for electrically connecting, in parallel relationship, alternate conducting sections of all of said second conductors.

5 In testimony whereof, I have hereunto

subscribed my name this 23rd day of Dec., 1914.
